UNITED STATES PATENT OFFICE.

JOHN W. JACKSON, OF DALLAS, TEXAS.

WASHING MACHINE.

Application filed August 7, 1925. Serial No. 48,742.

This invention relates to improvements in steam washers for clothes and it relates to certain novel features of arrangement of the parts thereof.

5 In the class of steam washers to which the invention relates there is provided a boiler and a heater combination, the boiler having a cone-shaped plunger member for lifting and moving the clothes and also a 10 cone-shaped bottom member which traps a certain amount of water to enable the water to heat rapidly.

It has been found in experience, however, that the plunger member is somewhat awkward in operation in handling varying amounts of clothes and also that the cone-shaped element is lifted from its seat during violent boiling of the clothes.

15 It is, therefore, an object of the invention to improve these parts by certain novel arrangements of construction whereby the plunger member is adjustable for handling varying amounts of clothes, the cone-shaped element being arranged so as to insure it 20 keeping its seat during the boiling operation.

With the above objects in view, the invention will be clearly understood by reference to the following description, in connection with the accompanying drawings, 25 and wherein:

Figure 1 is a side elevational view of a washer embodying the invention, partly in section.

30 Figure 2 is a plan view of the cone-shaped member.

Figures 3 and 4 are cross-sectional views taken along lines 3-3 and 4-4 of Figure 2.

Figure 5 is a plan view of the operating 35 lever for reciprocating the plunger; and

Figure 6 is a fragmentary side elevational view of Figure 5.

Referring more in detail to the various parts of the invention, 1 denotes the boiler section and 2 a heater with partition 3. The boiler 1 has a vacuum plunger cup 4 carried on a rod 5 and a cone-shaped water circulating element 6. The heater has a smoke outlet 7 and is supported on legs 45 8-8.

The improved features consist of the adjustment provided by the arrangement of an operating lever 9 with hand purchase 10, the lever being pivoted to a bar 11, in turn 50 pivoted to a lug 12 on the periphery of the boiler section 1. This lever 9 is shown in

detail in Figure 5 with its connecting parts in Figure 6. The lever 9 is connected by bolts 13-13 to two spaced bars 14-14 forming the remaining part of the lever. 60 These bars have spacers 15-15 and are loosely connected to the bar 11 previously referred to. At the point A the bars are curved, the two parts forming an opening for the rod 5 which has spaced perforations 65 5^a and reciprocates by means of the lever through the hole in the top of the boiler. Any one of these holes may receive the bolt 17 for adjusting the stroke of the vacuum plunger rod 5. A spring clip 18 is pivoted 70 to one of the bars 14 and holds the bolt in place. When adjustment of the bolt is desired the spring clip is moved aside as shown in dotted lines in Figure 6.

In Figure 2 is shown the means employed 75 for holding the cone-shaped element 6 in position. It will be observed that the boiler has a crimp in its periphery at 19 which is for the purpose of receiving the spaced lugs 20-20 of the element 6, and a slight pressure will spring the lugs into place and successfully hold this element in the position shown, just off the bottom or partition 80 3. The depending flange of the spacing element 6 is provided with circumferentially spaced openings 21 while the apex is formed with an opening 16, so that free circulation of water is assured. This latter arrangement prevents the clothes from 85 burning and permits free circulation of the water around the sides through said holes. The boiler has a cover 22 held in position by a spring catch 23.

From the foregoing it is obvious that the cone-shaped spacing element 6 is removably 90 positioned within the groove 19 of the boiler and in order to remove the same it is only necessary to insert an instrument or the finger of the operator within the opening 16 thereof and pull upwardly whereby the 95 radially extending lugs 20 will spring out of engagement with the groove 19 and the elements 6 removed from the boiler.

What is claimed as new is:

In a washing machine in combination, a 100 boiler having an internal groove extending about the inner surface and near the lower end thereof, a substantially cone-shaped spacing element arranged within the boiler near the lower end and provided with an 110 opening at its apex and having a peripheral depending flange also provided with

spaced openings, a series of laterally and radially extending lugs integral with and projecting at spaced intervals from the periphery of the cone-shaped element and engageable with the groove so as to rigidly yet removably support the element in spaced relation to the bottom of the boiler, and the spaces between the lugs and adjacent the grooves constituting passageways for allowing free circulation of liquid. 10

In testimony whereof I have signed my name to this specification.

JOHN W. JACKSON.
